UNITED STATES PATENT OFFICE.

HARRY VISSERING, OF KENILWORTH, ILLINOIS, ASSIGNOR TO THE OKADEE COMPANY, OF CHICAGO, ILLINOIS, A CORPORATION OF ILLINOIS.

LOCOMOTIVE-BOILER FRONT-END HINGE.

Application filed September 25, 1920. Serial No. 412,649.

This invention relates to closure supports and particularly to a support for the type of closure used in boilers of railway locomotives, and commonly termed the front end 5 and, as it is the plate for forming the forward end of the boiler. Although this invention is illustrated and described in connection with the closure for the front end of a locomotive boiler, it is to be understood 10 that the invention is capable of use in other relationships and with other types of construction.

This closure plate for the front end of a boiler is large and extremely heavy and according to approved railway practice is secured to the boiler front by a great number of stud bolts and nuts circumferentially arranged adjacent the outer edge of the front end plate. To make the joint between the 20 boiler front and the front end plate absolutely tight, the nuts are turned down as closely as possible. When it is desired to remove the front end plate to reach the inside of the boiler shell, the nuts are all removed and the front end plate moved away from the boiler shell. To loosen this front end plate and move it away from the boiler shell is rendered extremely difficult as there will be a tendency for the front end plates to 25 stick due to the rusting of the parts and of the action of the elements, aside from the factor of its great weight.

Still another difficulty encountered in the removal of this front end plate is that its 30 weight is such that a crane and tackle, or the like, is found necessary to carry the weight of the plate as soon as it is moved away from its position of support by the boiler. This necessitates that the engine be moved to a 35 spot where such crane and tackle are at hand.

The principal objects of this invention, are, therefore, to provide an improved arrangement whereby the front end plate can 40 be moved away from the boiler front without the use of the amount of time and effort now required; the provision of means whereby force can be manually applied to the front end plate at spaced points adjacent its outer edge and in the direction of movement of the closure plate to and from the boiler front not only to force the front end

plate away from the boiler front but also to again cause the front end plate to correctly seat itself on the boiler front; the provision of an improved construction by which the end closure plate can be moved away from the boiler front without at the same time moving the front end plate from its position of support by the boiler; the provision of a novel mechanism which will permit the front end plate to be moved first outwardly away from the boiler front and then swung to a side so as permit free access to the boiler interior without at the same time withdrawing the end plate from its position of support of the boiler; the provision of means whereby force may be applied alternately at different points on the front end plate for the purpose of facilitating the ease with which the front end plate may be removed; the provision of a device of the character described whereby the mechanism for moving the front end plate is operable in two stages, in the first of which it has no actuating relationship to the front end plate; together with such further and additional objects as may hereinafter appear.

In attaining the stated objects and certain additional benefits and advantages to be 50 hereinafter pointed out, I have provided a construction wherein—

Figure 1 is a front view of a sufficient portion of the boiler to show the supporting structure for the front end plate;

Figure 2 is a side view with the end closure plate seated on the boiler shell, and

Figure 3 is a side view showing the end closure plate moved away from the boiler front and swung to one side.

In the drawing, the boiler shell, 10, and the front end closure plate, 11, are held rigidly and tightly together by means of the circular row of stud bolts and nuts 12.

As these parts are all exposed to the elements, the front end plate will tend to stick to the stud bolts and to the boiler front, and it is extremely difficult to pry the front end plate loose from the boiler front and handle it without elaborate tackle. Furthermore, when it is pried loose special provision must be made to support the weight of the front end plate and to move it away from the boiler opening so as to be able to reach the

boiler interior. With this in view, I have devised certain novel features of construction now to be described.

Rigidly fixed to the outside surface of the boiler adjacent its front end at spaced apart points are the two bracket supports, 13—13. Each of these brackets is provided with upper and lower spaced ears, 14, 14, extending forwardly from the boiler front for a substantial distance, each being provided with the elongated openings, 15, 15 in vertical registration. Passing through these openings, 15, 15 for longitudinal reciprocation therein are the pins, 16, supported from the upper ears, 14, by the head, 17, and retained in position against accidental loss by the cotter pins, 18. To brace these ears, 14, against distortion, each bracket support, 13, is provided with the rib member 19.

20 The front end plate, 11, is mounted to swing about the pivot pins, 16, as a hinge by means of the hinge member, 20, extending outwardly beyond the front end plate 11, and rigidly supported therefrom by the bracket members 21, 21, each bracket member, 21, being provided with two hinge members 20. These members, 20, engage around the pins, 16, so as to cause the two to move together longitudinally, the pins being guided in such movement by the longitudinally extended slots 15.

By this arrangement I have provided a support for the front end plate from the boiler at two points spaced apart which will permit the front end plate being moved bodily in a right line away from the boiler front, and at the same time will maintain the end plate in a position of support from the boiler.

40 There is also thus provided an arrangement whereby after the front end plate, 11, has been moved bodily away from the boiler front, 10, and out of engagement with the stud bolts, 12, the front end plate, 11, can be swung bodily out of the path of the opening to the boiler front, to permit of free access to the boiler interior, while at the same time still retaining the end plate, 11, in supported relation to the boiler.

50 For additionally supporting and guiding the pin, 16, in its longitudinal movement, the bracket supports, 13, are each provided with the ear, 22, positioned intermediate the ears, 14, 14 and provided with an elongated slot similar to and in registry with the slots 15, 15 in the upper and lower ears 14, 14.

Each of the brackets, 13, is provided with the vertical rib, 23, within the outlines of the boiler, from which extends inwardly the boss, 24. The rib, 23, and the boss, 24, as well as the web portion, 25, of the brace member, 19, are each provided with a passage, all being in registry.

60 The passages through the members 23 and 24, are in registry and receive the screw-

threaded portion of the actuating bolt 26 provided at its front end with the circular portion, 27, which engages the pin, 16, as clearly shown in the drawing. (Figure 3.) The actuating nut, 28, is carried by the bolt, 26, between the web portion, 25, of the flange, 19 and the boss, 24.

As a result of this arrangement, when the nut, 28, is turned to move it against either the web, 25, or against the boss, 24, depending upon the direction in which it is turned, such member will act as an abutment for the nut, 28, and the continued rotation thereof will cause the bolt, 25, to travel either backwardly or forwardly. This will cause the hinge pin, 16, to move in the same direction, and will, of course, carry with it the closure member, 11.

It will be noticed that the space between the two members 24 and 25 is greater than the width of the nut 28. As a result, where it is desired to move the closure toward or away from the boiler front, there will be a free space provided for the travel of the nut 28 before it reaches its abutment at either end. This is of considerable importance, as it will be obvious that the nut, 28, as well as the closure member, 11, may stick, and the force necessary to rotate the nut would have to be sufficient to overcome not only the inertia, but as well the sticking tendency of the closure member, 11, and the nut 28.

By providing the aforementioned full space through which the nut is moved before this closure member is acted on, the two important results are attained of having all the force first applied to overcome the sticking tendency of the nut, and secondly a certain momentum is thus acquired which will make the force applied to the nut more effective in its actuation of the end plate 11.

The arrangement for giving the end plate, 11, its bodily movement is duplicated upon each hinge, which are shown at points substantially spaced from one another. The action of turning first the nut upon one hinge and then the other will be very similar to that used in which force is first applied at one point and that at another to pry an object loose.

Having thus described my invention and illustrated its use, what I claim as new and desire to secure by Letters Patent is—

1. In combination, a locomotive boiler having an opening, a closure therefor, and means for moving said closure bodily toward and away from said opening whether in alignment therewith or not, said means comprising two members movable relatively to each other independently of movement of said closure.

2. In combination, a locomotive boiler having an opening, a closure therefor, and means for moving said closure bodily from

and towards said opening whether in alinement therewith or not, said means comprising a member mounted for rotation, and a member movable thereby and relatively thereto and to the closure.

3. In combination, a locomotive boiler having an opening, a closure for said opening, securing means on the periphery of said opening for retaining said closure, and means for moving said closure bodily toward and away from said opening for engaging or disengaging the closure with said securing means, said means for moving the closure including a member mounted for rotation, and a member movable thereby and relatively thereto and to the closure, said moving means when operated displacing the closure whether in alinement with the opening or not.

20 4. In combination, a boiler, an opening therefor, a closure for said opening and means for supporting said closure for movement from and to the opening, said means comprising a plurality of hinges spaced from each other having independent pivots, one of the pivoted members of each hinge being fixed to the boiler, and the other of said members being displaceable in a plane laterally with respect to the pivots thereof.

30 5. In combination, a container element having an opening, a closure element for said opening mounted for movement from and toward the container element, and means for moving said closure from and towards said opening irrespective of the angular relationship of the container and closure elements, comprising a screwthreaded member carried by one of said first mentioned elements, and a rotatable member in screw-threaded engagement with said threaded member and acting against the other of said first mentioned elements.

6. In combination, a locomotive boiler, an opening therefor, a closure for said opening, means for supporting said closure from said boiler for bodily movement from and toward the boiler and pivotal movement with reference thereto, comprising a hinge pin movable longitudinally with reference to the boiler, and means for moving said hinge pin longitudinally, comprising a screw-threaded member carried by said hinge pin.

7. In combination, a locomotive boiler ele-
55 ment having an opening, a closure element

for said opening mounted for movement from and toward the boiler, and means for moving said closure from and towards said opening, comprising a screw-threaded member carried by one of said elements, a nut 60 threaded on said screw-threaded member and abutment members on each side of the nut and spaced from each other for a greater distance than the width of the nut.

8. In a structure of the character described, in combination, a closure and a seat therefor, and means for moving said closure to and from its seat irrespective of the angular relationship of the two, including a movable member and a member moved 70 thereby, the movement of said first member having two stages the first of which is ineffective to move the second member.

9. In a structure of the character described, in combination, a closure and a seat 75 therefor, and means for moving said closure to and from its seat irrespective of the angular relationship of the two, including a rotatable member and a second member movable longitudinally upon rotation of said first member, the first part of the rotation of said first member being ineffective to move the second member.

10. In a structure of the class described, in combination, a closure and a seat therefor and means for moving said closure axially with respect to its seat, including two relatively movable members and means for causing one of said members to move after a predetermined movement of the other.

11. In a structure of the class described, in combination, a closure and a seat therefor, and means for moving said closure axially with respect to its seat, including two relatively movable members, and means for causing the bodily movement of one of these members after a predetermined rotation of the other.

12. The combination with a boiler having an opening and a closure for said opening, of a hinge for said closure including a pair of pintles, and hinge members carrying same and fixed to the boiler, and means for bodily displacing said pintles relatively to each other and to the hinge members carrying same.

In testimony whereof I have hereunto signed my name.

HARRY VISSERING.
